SEAM FOR PAPER MAKER'S DRIER FELT
Thomas Hindle and Sam Lord, Blackburn,
England
Application April 25, 1934, Serial No. 722,358
In Great Britain May 17, 1933
5 Claims. (Cl. 24—33)

Papermakers' drier felts, consisting of heavy woven fabric having from one to four or even more plies, are used in various widths up to about 330 inches. The felts work around a bank of steam heated drying cylinders and intermediate rollers in a manner analogous to the operation of an ordinary driving belt. As the difficulties are very great in fitting a wide endless felt to the paper machine, it is generally found more convenient to fit an open-ended felt, and then to join the ends together, a process known as "seaming" the felt. It has been customary to seam or join such felts by sewing the ends together by hand. The seam made in this manner is not satisfactory as the large and irregular stitches pull out and break under tension, and often cause the felt to run into longitudinal creases, due to the partially transverse pull of the stitches. The time taken to sew the felt in this manner is considerable, and it is also frequently necessary to re-make the seam several times during the useful life of a felt, and very often a felt has to be discarded in consequence of its ends being unsuitable for re-sewing although the remainder of the felt is capable of further service.

Drier felt ends have been joined by a lap seam riveted together. In such a seam, there is a strong tendency for the rivets to bend over in the fabric, when they may damage the paper in manufacture.

The object of this application is to provide a new and novel method of joining or seaming papermakers' felts, and to provide a seam of very great mechanical strength which has no inherent tendency to cause the felt to crease, and which permits the ends to be fastened together in a very expeditious manner with the felt in position on the paper machine.

The invention comprises a loop about two inches wide formed along each end of the belt, the folded over or back portion thereof being cut with a number of narrow slots longitudinal of the felt and spaced equidistantly across it and a number of links of approximately H formation inserted in the respective slots by which the two ends of the felt are mutually attached.

The invention will be fully described with reference to the accompanying drawings:—

Fig. 1 is a perspective view of one form of the invention.

Fig. 2 is a plan of one end of felt extended with slots cut therein.

Fig. 3 is a perspective view of one end of felt with loop formed thereon.

Fig. 3a is a perspective view of a link D.

Fig. 4 is a plan partly in section showing jointed end of felt.

Figs. 5 and 6 are perspective view and plan partly in section showing a modified construction.

Fig. 7 is a perspective view showing another modification.

Figs. 8, 8a, and 8b are various forms of connecting links.

In its simplest form shown in Figs. 1 to 4 about four inches at each end *a* of the felt A is folded over to the back of the felt and sewn down by several rows of machine stitching thus forming a loop about two inches wide along each end of the felt, the folded-over or back portions of the loops are slit at intervals forming narrow slots B longitudinal of the felt spaced equidistantly along the ends of the felt. Each slot B is about two inches in length and terminates on the extreme tip of the fold i. e. on the felt end, in a circular or substantially round hole *b*. The slots may be spaced apart one to two inches or more according to requirements.

The edges of the slots B in the felt A may be reinforced and prevented from fraying by sewing around each slot and also by lines of sewing across the width of the felt adjacent to the slots. Alternatively, or additionally, the edges of the slots B may be treated with varnish or gum, or by any similar means of preventing fraying.

The two ends of the felt A, prepared as above described, are brought together and mutually attached by links D, approximately of H-formation. These links may be made from any material having the requisite strength, and may be steel stampings finished by galvanizing, electro-plating or other treatment providing resistance to chemical action. Alternatively, the links D conforming in outline with the general shape described, may be made from wire, bent and either brazed or welded together (see Fig. 8).

The parallel legs *d* of the H-shaped links D are slightly shorter in length than the spacing between adjacent slots in the ends of the felt, and the length of the cross-bar *d1* connecting the two parallel legs is approximately equal to two thicknesses of the felt.

In joining the two ends of the felt, one leg *d* of a link D is inserted through a slot B in one end of the felt, and the other leg is inserted through the corresponding slot B in the other end and further links are similarly inserted until all the slots are occupied, and the two ends of the felt closely linked together. The legs *d* of the links D lie in the ends of the loops, and the cross-bars *d1* project through the slots from one

end of the felt to those in the other end and serve to carry the tension applied to the seam and felt when running on the paper machine.

In the form shown in Figs. 5 to 7 the slotted loops *a1* are made from separate pieces of fabric sewn or attached in any desirable manner to the ends of the felt *A* leaving the ends *a2* to project beyond the loops sufficiently to butt together (Fig. 5) or to overlap to a greater or less degree (Fig. 7). In this case, the cross-bar *d1* of the H-shaped link *D* is longer, say equal to four or eight thicknesses of felt. The links *D* are inserted in the manner above described, from the back of the felt.

15 In any of the forms of this improved seam, the links are protected by the fabric forming the loops or by the felt proper from contact with the surfaces either of the drying cylinders or intermediate rollers of the paper machine, thus preventing damage to the paper, the cylinders or rollers, or to the seam itself. As the links *D* are separate units, each joining a small width of felt, no transverse strains are imposed on the felt at the seam with the result that there is no inherent tendency for the felt to crease.

20

25

What we claim as our invention and desire to protect by Letters Patent is:—

1. A paper maker's drier felt constructed with a loop about two inches wide at each end cut

with a plurality of narrow slots disposed longitudinally of the felt and spaced equidistantly across it.

2. A paper maker's drier felt constructed with a loop about two inches wide at each end cut with a plurality of narrow slots disposed longitudinally of the felt and spaced equidistantly across it and means by which the two ends of the felt are mutually attached.

3. A paper maker's drier felt formed with each end cut with a number of slots longitudinally of the felt, and with each end folded over to the back and sewn down by several rows of machine stitching to form a loop about two inches wide along each end.

4. A paper maker's drier felt as in claim 1 formed with a slotted loop at each end made from separate pieces of felt stitched thereto and leaving the ends of the felt to project beyond the loops either to butt together or overlap.

5. A paper maker's drier felt constructed with a turned over loop about two inches wide at each end, a plurality of narrow slots cut therein longitudinally of the felt, a plurality of shaped links inserted in the respective slots projecting across from one loop to the other and joining together the two ends of the felt.

THOMAS HINDLE.
SAM LORD.
